UNITED STATES PATENT OFFICE

2,325,496

TOY

Jack F. Fleming, Milwaukee, Wis., assignor to
Walter A. Hartwig, Milwaukee, Wis.

Application May 23, 1942, Serial No. 444,243

3 Claims. (Cl. 272—52)

This invention relates to improvements in toys, and more particularly to a novel hobby horse.

An object of the invention is to provide a device of the type which will suggest more realism than is common in devices of the type now in use, the latter usually employing cumbersome rockers and base frames. The present invention suspends and rocks the horse or other animal on the four legs without the necessity of any base or rocker attachments.

Another object of the invention is to provide a device of the type which may easily be moved from place to place by a child user, and which because of its construction and operation will effect a minimum of wear and tear on the floor or ground surface on which it is used.

Other and further objects of the invention will appear as the description proceeds, reference being had to the accompanying drawings, in which:

Fig. 1 is a side view in elevation of a toy embodying my invention.

Fig. 2 is a side view partly in elevation and partly in vertical section.

Fig. 3 is a rear view partly in elevation and partly in vertical section, taken on line 3—3 of Fig. 2.

Fig. 4 is a plan view taken on line 4—4 of Fig. 2.

Fig. 5 is a view in perspective and partially broken away, of one of the adjustable stirrups.

Fig. 6 is a fragmentary view showing the coil spring and socket structure.

Fig. 7 is a side view partly in elevation and partly in section of a modified form of the invention.

Fig. 8 is a view on line 8—8 of Fig. 7.

In the drawings, numeral 10 refers to the device generally, having a fabric body covering 11, placed over a frame 12, comprising two arcuate end pieces 13 and 14, the side members 15, and the back members 16. A front spreader block 17 and a rear spreader block 18 are held between the members 16.

The frame 12 has under the fabric covering 11, an arcuate sheet of material 19, extending over the top of said frame 12, from one side member 15 to the other.

The forelegs, 20, are drilled at 21, adjacent their upper ends to receive the bolt 22, which latter pivotally connects the said legs 20 to the back members 16. Washers, 23, are carried on the bolt exteriorly of the back members, and a pair of nuts 24 threadingly engage the outer ends of said bolt 22. The holes drilled at 21 are

slightly oblique, so that the legs 20 are disposed in a wider spaced relation at the bottom than at their top portions.

A second horizontally disposed bolt 25 joins the legs at 26 thereof, the said legs being spaced by the wedge-shaped blocks 27, washers 28 and the spacer element 29. The lower ends of the legs 20 are provided with foot plates 30, and the inwardly disposed buttress blocks 31.

10 The legs 20 are countersunk to accommodate the nuts 32 threadingly engaged with the ends of the bolt 25.

The hind legs 33 are secured pivotally by bolt 34 to the rear end portion of the back members 16, and are pivotally engaged with the rear portion of the spacer element 29 by means of the bolt 35, in the same manner as the legs 20.

The spacer element 29 carries on its upper surface the blocks 36 and 37, the latter having with 20 in their outer ends the socket formations 38, provided with the rubber plugs 39 to act as a seat for the coil springs 40. Free dowel pins 41 are held floatingly within the springs 40, and act to limit the compression of said springs. Metal guard plates 42 are interposed between the outer ends of springs 40 and the end frame pieces 13 and 14, and are secured to the latter.

An animal neck 45 has an angular cut-out portion at 46 thereof, and is fastened by means of bolt 47 and wing nut 48 to the front end frame portion 13, and by means of the screw 49 to the front spreader block 17. The neck 45 is apertured at 50 and has fixed therein the double grip bar 51. It will be understood that the head 52 and other physical appearance features may be varied to represent many other animal species. The tail element 53 having a similar angular cut-out portion, is fastened by means of the screw 54 to the spreader block 18, and by means of screw 55, to the rear frame member 14. A saddle 56 rests in an appropriate position on the top of the device, and is backed by the saddle rest 57, which latter is secured by the screw 58 to the front of the tail member 53. The saddle 56 has dependently attached thereto, the stirrup strap 59, in turn connected to the stirrup shield 60, which latter is secured at its lower edge to the foot rest 61.

In the modified form of the invention shown in Figs. 7 and 8, the spacer element 29 is provided with tabs 62 and 63. Long, tensile springs 64 and 65 are secured respectively to these tabs and extend nearly the entire length of the interior of the body to respective points of attachment 66 and 67 to the ends 13 and 14. In this form of

the invention, the double grip bar 51 is inserted in a post 68 which is forked at 69—70. The forks 69 and 70 are secured to the spacer element 29. It will be noted that the post 68 extends through a slot 71 in the top of the body. Thus the child using this embodiment of my invention is seated behind the post 68 and may use the double grip bar to assist in rocking the hobbyhorse.

In the preferred form of the invention, a child user may rock the device backwardly and forwardly against the resistance of springs 40, by merely swinging his weight. In the modified form of the invention, he uses the lever to assist this action.

It will be understood that the device is capable of many modifications in structure and design, without departing from the spirit of the invention within the scope of the appended claims.

Having thus described my invention, what I claim and desire to secure by Letters Patent of the United States, is:

1. A device of the character described comprising a body, legs for said body pivoted at their tops within the body, a member pivoted to all the

legs spaced from the top thereof, and spring means between said member and the body normally maintaining said legs in vertical alignment.

5 2. A device of the character described comprising a body, legs for said body pivoted at their tops within the body, a horizontal member pivoted to all the legs spaced from the top thereof, and spring means between said member and the 10 ends of said body normally maintaining said legs and body ends in vertical alignment.

3. A device of the character described comprising a body, legs supporting said body pivoted at their tops within the body, a horizontal member pivoted to all the legs each at a point uniformly spaced from the top pivot thereof, means on said horizontal member having socket formations extending endwise thereof, coiled springs freely held in the socket formations and normally exerting pressure within the ends of said body to keep the same in erect position with said legs in vertical alignment.

JACK F. FLEMING.
